UNITED STATES PATENT OFFICE

150,765

DESIGN FOR A BICYCLE

Hugh Harman, Beverly Hills, Charles F. McGirl,
Van Nuys, and Harvey K. Greenlaw, Los Angeles, Calif.

Application September 3, 1946, Serial No. 133,034

Term of patent 3½ years

(CL. D90—8)

To all whom it may concern:

Be it known that we, Hugh Harman, Charles F. McGirl, and Harvey K. Greenlaw, citizens of the United States residing, respectively, at Beverly Hills, Van Nuys, and Los Angeles, in the county of Los Angeles and State of California, have invented a new, original, and ornamental Design for Bicycle, of which the following is a specification, reference being had to the accompanying drawing, forming part thereof.

The drawing illustrates a bicycle embodying our new design in which

Fig. 1 is a side elevational view of the bicycle;
Fig. 2 is a front elevational view of the same;
Fig. 3 is a bottom plan view; and
Fig. 4 is a rear elevational view.

We claim:

The ornamental design for a bicycle, substantially as shown.

HUGH HARMAN.
CHARLES F. McGIRL.
HARVEY K. GREENLAW.
